TRANSOM ADAPTER FOR THE JET-EXHAUST CONDUIT FROM A WATER-JET POWERED BOAT

Robert K. Ridlon, Anaheim, Calif., assignor to H. N.
Bailey & Associates, Santa Ana, Calif.

Filed Mar. 29, 1971, Ser. No. 129,316

Term of patent 14 years

Int. Cl. D12—99

U.S. Cl. D71—1 S

FIG. 1.

FIG. 2.

FIG. 3.

FIG. 5.

FIG. 4

FIG. 1 is a front isometric view of the transom adapter for the jet-exhaust conduit from a water-jet powered boat, showing my new design;

FIG. 2 is a front elevational view thereof;

FIG. 3 is a side elevation thereof;

FIG. 4 is a bottom plan view; and

FIG. 5 is a rear isometric view.

The side not shown in FIG. 3 is a mirror image of the side shown therein.

I claim:

The ornamental design for a transom adapter for the jet-exhaust conduit from a water-jet powered boat, substantially as shown and described.
